L. A. GOODWIN

COOLING SYSTEM FOR HOUSES OR ROOMS

Filed Sept. 24, 1921

L. A. Goodwin
Inventor

By
Watson E. Cobeman Attorney

UNITED STATES PATENT OFFICE.

LEWIS A. GOODWIN, OF CORA, MISSOURI.

COOLING SYSTEM FOR HOUSES OR ROOMS.

Application filed September 24, 1921. Serial No. 502,917.

To all whom it may concern:

Be it known that I, LEWIS A. GOODWIN, a citizen of the United States, residing at Cora, in the county of Sullivan and State 5 of Missouri, have invented certain new and useful Improvements in Cooling Systems for Houses or Rooms, of which the following is a specification, reference being had to the accompanying drawings.

10 This invention relates to systems for causing cool air to be discharged into rooms of houses, and more particularly to means of this character in which the cool air is taken from an underground chamber so that 15 the air is cooled not by ice or like means but by the natural coolness of the earth.

The general object of the invention is to provide a cooling system of this character which is very simple, which may be therefore 20 cheaply installed, and which is thoroughly effective.

Another object is to provide means whereby the air may be drawn positively into the chamber within which the air is cooled and 25 forced into the several rooms, means being also provided whereby the discharge of air into the several rooms may be controlled.

Other objects will appear in the course of the following description.

30 My invention is illustrated in the accompanying drawings, wherein:—

Figure 1 is a diagrammatic sectional view of building having my improved cooling means applied thereto;

35 Figure 2 is a fragmentary sectional view showing a slight modification;

Figure 3 is a diagrammatic view of the building with my cooling system applied thereto.

40 In these drawings, it will be understood that I have illustrated my system diagrammatically and that the details of the parts and their arrangement will depend largely upon the building to which the cooling sys-

45 tem is to be applied. In Figure 1 I have illustrated my cooling system as applied to a house having a number of rooms A. Exterior of the house or in any desired location there is formed a chamber 10 which is disposed 50 preferably beneath the ground. This chamber as illustrated is to be lined with concrete 11 or with brick or constructed in any suitable manner. The

chamber 10 when and where a double conductor is used constitutes a chamber for air, 55 and may be partly or entirely filled with water. Entering this chamber is an intake pipe 12 which may be provided with a cap 13 at its inlet and which would prevent the entrance of rain but permit the entrance 60 of air, this pipe 12 extending to or near the lower end of the cooling chamber or pit 10 and then extending upward through this chamber, as at 12^a, nearly to the upper end thereof and then extending out of this 65 chamber at an inclination and extending to a point beneath or to the side of one of the rooms and then upward through the first room of the series, being connected at its upper end preferably to a combined suction and blast fan 14. This fan may be propelled in any suitable manner and from the casing of this fan extends a pipe 15. This pipe may open directly into the room. From the pipe 15 extends a pipe 16 which 70 extends into the other rooms of the building or apartment, this pipe 16 being provided with downwardly extending branches 17 discharging cool air into the upper portion 75 of the room. 80

The outlets from the pipe 16 may be arranged in any suitable manner and these outlets are preferably provided with caps 18 which may be adjusted when desired to permit or prevent the entrance of air. Obviously valves or dampers may be used for the same purpose. Preferably a return 85 pipe 19 is arranged to open from the lower portion of any one or all of the rooms, this return pipe 19 preferably extending into the 90 chamber 10 at the upper portion thereof and being operatively connected to the vertical intake pipe 12 so that this warm air which escapes from the room is carried back into the pipes 12 and circulated through the pipe 95 12 and 12^a back into the rooms along with air which may be drawn from the exterior of this chamber 10. The pipe 19 within the room is provided with an extension on which a cap 13^a is mounted. This extension may 100 be made in various lengths according to the size of the room and also to permit the capped end of said suction pipe to be so positioned as to best remove the warm air. When the cap 13^a is closed the conductor 105 pipe 12 will then serve to supply air en-

tirely from the exterior. One or both of the caps 13 and 13^a may be partially closed.

It is obvious that the present invention may be used in cold weather, to raise or equalize the temperature in the rooms, as the temperature of the earth will be higher than that of the outside air. The connected pipes 12 and 12^a in Figure 1 rest upon suitable supports 12^c. Furthermore the pipe 10 or conductor 12 may be flattened at any suitable location or to any extent, as shown at 12^f. Also the lower end of 12^a in Figure 1 may be disconnected from 12, as shown in Figure 2, thereby converting into a single 15 conductor rather than a double conductor. I do not wish to be limited to the use of the inlet pipe 12, as the pipe section 12^a may extend from the fan 14 down to the bottom of the chamber 10 and take its air 20 from there, the upper end of this chamber 10 being in that case open.

In Figure 2, I show a construction wherein the pipe 12^x is the equivalent of the pipe 12. In Figure 2, I have illustrated 25 the fan 14 as being upon the exterior of the house instead of the interior thereof and the pipe 12^a as extending upward from the ground at or near the exterior of the wall of the house.

30 In Figure 2 an air inlet pipe 19^a is shown as extending from the air chamber 10 to one of the rooms A, to conduct the air from the air chamber 10, or from the exterior thereof, to one of the rooms A. If desired, 35 either of the caps 13 or 13^a in Figure 2 may be removed, to allow air to enter the chamber 10 from the exterior. Also, in Figure 2 the pipes 12^a and 12^x are disconnected as shown and are supported in position by any 40 suitable supports, such as 12^b.

Preferably each of the discharge outlets or branches 17 will be provided with a cap 18 in the form of a cone-shaped member having braces attached to a collar 18^a. This 45 collar may have screw-threaded engagement with the pipe 17 or otherwise arranged so as to permit this cone-shaped member to be shifted toward or from the mouth of the pipe to thus control the distribution of air.

50 Of course, the cone-shaped member has a central portion 18^b larger than the aperture of the discharge branch, so that the cone-shaped member may be screwed home to close the outlet from the branch 17.

55 It will be noted that in all the forms of my invention the air chambers are the same, the difference being that in one case I use a single suction tube drawing air from near the bottom of the chamber, and in the other 60 case the double suction tube which draws the air from a point above the ground or from a room, and draws it through the air chamber. The discharges from the pipe 16 are the same in all cases. The air chamber 65 may be dug in the ground or a well or cellar

may be used for the air chamber, and obviously in the latter case a pump may be used to withdraw any water which may collect in the air chamber. The air chamber may be walled or cemented, sides and bottom, and covered on top. Any number of air chambers may be used about a barn or house or in places where cooling is desired. I do not wish to be limited to the particular fan for moving the air as it may be of any 70 size or type. It may be run by electricity, wind mill, hand, or any other suitable power.

In Figure 3 I illustrate diagrammatically that the pipe leading from the chamber 10 may extend underground around the house 80 before entering the house instead of extending directly into the house, as in Figures 1 and 2. This pipe I have designated 12^d to distinguish it from the pipes 12^a which enter the house directly, but it will be understood 85 that it is to all intents and purposes the same pipe.

It will be obvious that the conducting pipe 12, particularly if out of doors, as in Figure 1, may be insulated by suitable packing 90 material. An air pump may be used in place of the fan for withdrawing the air from the pipe 12 when ejecting it into the rooms of the house. I do not wish to be limited to the use of a chamber such as 10 filled with 95 air cooled by contact with the ground, as this chamber might be filled with water which would be kept cooled by being underground.

While I have described my invention as applicable to houses, it will be understood 100 that it also may be applied to a ship except that the air chamber in this case would be under water.

I claim:—

1. The combination with a building, of 105 an underground chamber, a pipe extending from the lower end of the underground chamber up through said chamber and then out into said building and having a plurality of discharge openings, means disposed 110 in the length of the pipe and inward of said discharge end of the pipe for positively drawing air through the pipe from the intake end thereof and discharging it out through said discharge openings, a pipe section 115 leading downward into said underground chamber and having an inlet opening above the ground, and a pipe leading from said building adjacent the floor thereof, extending into the upper end of the underground chamber and discharging into said second named pipe adjacent the inlet end thereof.

2. The combination with a building, of 125 an underground chamber, an intake pipe extending from the surface of the ground downward into said chamber to a point adjacent the bottom thereof, then extending upward and out of the chamber below the upper end thereof and into said building 130

and having a plurality of discharge openings in the building, means disposed in the length of the pipe and inward of the discharge end of the pipe for positively drawing air 5 through the pipe from the intake end thereof and discharging it through said discharge openings, and a pipe leading from said

building adjacent the floor thereof and discharging into the upper end of the first named pipe adjacent the top of the underground chamber. 10

In testimony whereof I hereunto affix my signature.

LEWIS A. GOODWIN.
